INSECT ELECTROCUTOR

William M. Frost, Spokane, Wash.

Application January 16, 1928, Serial No. 247,105

9 Claims. (Cl. 43—112)

The present invention relates to insect electrocutors, and particularly to devices of that character which comprise electric conductors arranged upon a hollow frame or support within or upon which some means for attracting insects may be placed. The general subject-matter and a specific embodiment of the invention are disclosed in my copending application Serial No. 177,610, filed March 23, 1927 which has matured 10 into Patent 1,730,814, issued October 8, 1929.

The several embodiments of the invention disclosed herein are particularly adapted for use in orchards and gardens, where moths and other insects injurious to growing crops are prevalent.

14 The principal object of my present invention is the provision of an insect electrocutor of such shape, design and construction that insects will be attracted to the device, and, flying about it, will be caused to fall upon or in close proximity to electrically charged elements, or electrodes, by which they will be electrocuted. The term electrodes, used in this connection, is intended to refer to electrically charged elements of any shape or form and from which an electrical 20 charge may be produced under the circumstances and conditions explained herein.

Another object of the invention is the provision of an insect electrocutor of the general type referred to which will have one or more of its 25 walls in the form of an electrocuting element or elements resembling a grid or grids so constructed and disposed that the device will operate more efficiently and produce improved results.

A further object is the provision of an insect electrocutor of the character of construction and operation in which each of the electrode elements employed may be formed of a single piece of metal or of a small number of assembled similar electrode units.

40 A further object is the designing of the electrode elements in such fashion that they can readily be produced from sheet metal by metal-stamping machinery of any well-known type.

A still further object is the provision of a device of this character which can be readily assembled and which can therefore be easily and economically manufactured.

These objects I attain by the arrangement of spaced parallel electric conductors secured upon 50 a hollow support or frame of special shape and construction.

I preferably employ a support of such configuration that electric conductor elements may be so arranged thereon in spaced parallel relation 55 as to form one or more grid-like elements lying

in one or more inclined planes. Most conveniently the position of the grid construction will substantially coincide with the periphery of the supporting frame.

The frame may be of any desired configuration 60 which includes an inclined face or faces upon its outer surface. The most convenient and satisfactory shapes, from the standpoint of production and operation are the pyramid and the cone. The conical or frusto-conical and the pyramidal 65 or frusto-pyramidal forms may be manufactured conveniently and economically. They permit the ready installation of the conductors or electrodes upon the support and are especially adapted for the application thereto of ribs or projections 70 against which insects will strike while circling about the device.

Other objects and advantages of the invention will be apparent from the following specification and drawing, in which like numerals refer to like 75 parts, throughout the several views.

Figure 1 of the drawing is a perspective view of a device of general pyramidal shape constructed in accordance with my present invention.

Figure 2 is a horizontal sectional view through 80 a corner of the device of Fig. 1, showing the method of securing the electrodes in position, the electrode elements on the rear faces of the device being omitted for the sake of clarity of illustration.

In its preferred form my invention comprises 85 spaced horizontal or substantially horizontal conductors supported in parallel relation upon a frame of generally frusto-pyramidal shape. An example of this preferred form is shown in 90 Fig. 1. Various kinds and constructions of conductors or electrodes may be secured or attached to the frame. For example, they may be in the form of stamped metal strips or ribs, as illustrated in Fig. 1.

The device shown comprises a base 1, top 2 and corner posts 3, the latter being of insulating material. The base and top may be of metal. Supported upon this frame, and insulated from the metallic parts, are electrodes 4 and 5. The 100 inner electrode 5, of frusto-pyramidal shape, is disposed within the posts 3, the corners of the electrode being recessed to fit the posts.

The outer electrode 4 is also frusto-pyramidal in shape. Its corners fit closely about the corner 105 posts 3. This electrode, like electrode 5, is suitably insulated from base 1 and top 2.

Each of the electrodes 4 and 5 may be formed of four substantially flat electrode elements, each being a grid-like structure comprising marginal 110

strip portions 7 and 8 and spaced parallel ribs or vanes 9 and 10 bent out of the plane of the marginal portion and connected to the respective marginal portions by arms 13, 14. Each of these 5 electrode elements may be from a single sheet of metal, suitable cutting dies being used to cut the ribs 9, 10, arms 13, 14, and their connecting strips 7 and 8 in the proper outline and stamping dies of proper configuration then being employed 10 to force the ribs to their proper position relative to the marginal portions of the electrode.

After the electrode elements have been formed in the manner described above they are assembled, as in Fig. 1, to produce the complete electrodes 4 and 5. The several grid-like electrode elements of electrode 5 may be secured together by welding, or in any other suitable way. The similar elements of the outer electrode 4 are assembled upon the outer side of the corner posts 20 and secured together in any suitable manner, as, for example, by a tongue and groove connection 13. When assembled, each corner of the outer electrode 4 has a recess in which one of the corner posts is received.

25 The arms 13 of outer electrode 4 extend inwardly and arms 14 of inner electrode 5 outwardly, the ribs or vanes 9, 10 consequently being positioned one above another in a plane between the planes of the marginal portions of the respective electrodes.

Each rib 9, 10 may be bent to lie at any desired angle. It is preferable to bend all of the ribs to such an extent that the maximum amount of light from an electric lamp 15 or other source

35 of illumination may pass between them. Care must be observed, however, not to space the ribs so far apart that insects will be able to pass between them without being electrocuted.

In operation, the electrodes 4 and 5, respectively, are supplied with current of opposite polarity from a transformer (not shown) preferably mounted in the top 2 of the device and connected to the lighting circuit through lamp 15. Thus the lighting circuit can be used both to 45 attract the insects and to electrocute them.

In use, insects are attracted to the device at night by the light from lamp 15, and in the daytime by suitable bait placed within the hollow frame. Moths and other insects approaching 50 the device will circle rapidly about it, gradually closer and closer to the light or bait. Their circular or spiral path will eventually bring them so close to the device that they will either come into contact with the charged electrodes or strike 55 against one or the other of the projecting ribs formed at the corners of the device by the junction of adjacent electrode elements of electrode 4. When the latter occurs, the insects, stunned or disabled by the blow, will fall toward the ground. If the sides of the device were vertical or inwardly inclined, the insects would fall clear 60 of the device and would in most instances not be killed. With my present device, however, they will fall directly upon one of the inclined grids formed by electrodes 4 and 5, causing their immediate electrocution.

I claim:

1. In an insect electrocuting trap of cage-like 70 form, the combination with a support, of a trap portion comprising a pair of cage-like electrodes one within the other, said electrodes including alternately spaced overlapping horizontally disposed positive and negative blades, said blades 75 being turned about their longitudinal axes to

place only their longitudinal edges in the inner and outer surface planes of said electrodes.

2. An insect electrocuting trap comprising cage-like electrodes, one within the other, said electrodes including spaced alternating blades 80 disposed in parallel horizontal planes.

3. An insect electrocuting trap comprising cage-like electrodes one within the other, each of said electrodes including spaced blades disposed in parallel planes and the blades of each 85 electrode being projected edgewise between adjacent blades of the other electrode into overlapping relation.

4. An insect electrocuting trap comprising cage-like electrodes one within the other and each having blade-supporting strips, the inner electrode including horizontally disposed blades connecting its blade-supporting strips and projecting outwardly, the outer electrode including 90 horizontally disposed blades connecting its blade-supporting strips and projecting inwardly into overlapping relation with the blades of the inner electrode and being in spaced alternating arrangement therewith, the horizontal planes of all 95 of said blades being parallel.

5. An electric insect trap comprising a pair of upwardly tapering, cage-like electrodes, one within and insulated from the other, each electrode including blades disposed edgewise in parallel horizontal planes, the blades of the inner 100 and outer electrodes being in spaced alternating relation and projecting respectively outwardly and inwardly to overlap and lie in the same inclined plane.

6. An electric insect trap comprising a cage-like electrode formed of peripherally spaced inclined blade-supporting members and spaced blades connecting said members, a second cage-like electrode formed of peripherally spaced inclined blade-supporting members and spaced 115 blades connecting said last-mentioned members, all of said blades being disposed edgewise in parallel horizontal planes and one of said electrodes being disposed within the other and insulated therefrom, with the blades of one electrode lying 120 between and in spaced relation with the blades of the other electrode in the same inclined plane.

7. The combination in an insect electrocuting trap with a housing and a transformer therein, of a trap portion comprising a pair of upwardly 125 tapering cage-like electrodes below said housing, one of said electrodes being disposed within and spaced from the other, said electrodes being connected with said transformer and formed of a pair of upper conductor bands, one within and 130 spaced from the other, a pair of lower conductor bands, one within and spaced from the other, spaced inclined conductor strips respectively connecting the pairs of inner and outer bands, and blades connecting said inclined strips, said 135 blades being disposed edgewise in parallel horizontal planes, and the blades of the inner and outer electrodes being in spaced alternating relation and projecting respectively outwardly and inwardly to overlap and lie in the same inclined plane.

8. An insect electrocutor comprising two spaced concentric frusto-pyramidal electrodes, the side walls thereof being formed of grid-like members including parallel blades, and the blades 145 of each of said members being bent edgewise toward those of the corresponding member of the other electrode to lie in substantially the same plane in spaced alternating relation.

9. In an insect electrocutor, upwardly tapering 150

cage-like electrode frames, one within and spaced from the other, spaced electrode blades supported on the frame of the inner electrode and disposed in parallel planes to form an upwardly 5 tapering grid-like structure, spaced parallel electrode blades supported on the frame of the outer electrode, portions of the blades of each elec-

trode being bent to lie edgewise in the plane of the blades of the other electrode and to alternate therewith, means within said cage-like electrodes for attracting insects, and means for supplying adjacent electrode blades with current of opposite polarities. 80
